United States Patent Office.

GEORGE T. PARRY, OF PHILADELPHIA, PENNSYLVANIA.

Letters Patent No. 89,069, dated April 20, 1869.

IMPROVEMENT IN VELOCIPED.

The Schedule referred to in these Letters Patent and making part of the same.

To all whom it may concern:

Be it known that I, GEORGE T. PARRY, of the city and county of Philadelphia, and State of Pennsylvania, have invented a new and useful Locomotive-Machine, actuated by pedal or manual power, which I denominate "The Excelsior Velocipede."

My invention is designed to provide a vehicle to be propelled by the rider, which shall be simple and substantial in construction, economical in cost, easily operated, exempt from danger, adaptable to the gauge of any roadway or street-railway, susceptible of efficient and safe use without previous instruction or training on the part of the operator; free from lateral motion; not liable to be upset on encountering an obstruction or inequality in the way, when in rapid motion, and which is suited to the use both of males and females.

The following is a full, clear, and exact description of my invention, reference being had to the accompanying drawing, making part of this specification, and representing a front view of the machine.

A represents the central frame, strong and rigid, made of iron, steel, or other suitable material, from which depends the casing B B B that supports the rider's seat, which is placed equidistant from each wheel, and below the line of the axles, thus preserving the equilibrium of the velocipede, giving it steadiness of motion and enabling it to surmount obstacles with safety.

From the front rim of the central frame extends the projection C, terminating in a horizontal cross-piece, D, upon which are pivoted the central cog-wheel a and the side cogs b b, at the inner extremities of the horizontal arms c c, pivoted to the levers E E, that are affixed by screws, or otherwise, to the slides F F.

These slides are fitted to the outer rim of the central frame, and serve as the inner bearings of the axles G G.

The slides are fastened to the central frame by flanged plates at the top and bottom, or by other appropriate mechanical means.

If desirable, the axles may be protracted inwardly and pass through the rim of the central frame, so as to connect or disconnect with each other, at the will of the operator, by means of a clutch, or other suitable mechanical device.

The outer extremities of the axles terminate in the hubs of the wheels, situated parallel to each other on a horizontal plane.

These wheels may be made of any suitable materials and dimensions.

The axles severally revolve on anti-friction rollers, enclosed in suitable boxes, H H, one of which is placed

near the hub of the wheel and the other near the slide F.

The anti-friction boxes are held in position by connecting-bars, or their equivalents, extending from one box to the other, and fastened thereto.

Between these boxes, on each axle, is the crank I, which is rotated by the vertical lever K, to which motion is communicated from the treadle L, worked by the foot of the operator.

The treadle-bar passes through a slot in the vertical side of the casing, and is held in position by a pivot, or other suitable mechanical contrivance.

A crank movement, operated by manual power, may be substituted for the treadle arrangement to propel the machine.

The process of steering the machine is as follows:

The rider moves the tiller M in the proper direction to the right or left, which rotates the cog-wheel a that transmits motion to the side cogs b b, and these actuate the horizontal arms c c, and they, in turn, impart a lateral movement to the levers E E, that operates the slides F F, whereby a forward impetus is communicated to one wheel and axle, and a corresponding backward impetus is given to the other wheel and axle, and thus the operator is enabled to guide the machine in any direction, and to change its course at pleasure.

If desired, the velocipede may be steered by means of rods, cords, or their equivalents, connected with the outer anti-friction box on each axle, and controlled by the operator by suitable mechanism in the front and rear of the central frame.

A brake, if required, may be used in connection with the running-gear to regulate the speed of the velocipede and control its movement in descending hills.

What I claim as my invention, and desire to secure by Letters Patent, is—

1. The steering-apparatus, composed of the projection C, terminating in the horizontal cross-piece D, the cog-system a, b b, the horizontal arms c c, the vibrating-levers E E, the slides F F, and the tiller M, or the equivalent of any of the foregoing constituent parts, arranged, constructed, and operating in the manner and for the purpose substantially as described.

2. The combination of the steering-apparatus, the central frame, and the running-gear, arranged, constructed, and operated in the manner and for the purposes substantially as described, and forming a locomotive-machine, propelled, guided, and controlled by pedal or manual power.

GEORGE T. PARRY.
